UNITED STATES PATENT OFFICE.

WERNER ED WYNNE, OF DURANT, MISSISSIPPI.

CHURN-DASHER.

No. 833,656.

Specification of Letters Patent.

Patented Oct. 16, 1906.

Application filed July 13, 1906. Serial No. 326,130.

To all whom it may concern:

Be it known that I, WERNER ED WYNNE, a citizen of the United States, residing at Durant, in the county of Holmes and State of Mississippi, have invented certain new and useful Improvements in Churn-Dashers; and I do hereby declare the following to be a full, clear, and exact description of the invention, such as will enable others skilled in the art to which it appertains to make and use the same, reference being had to the accompanying drawings, and to the letters of reference marked thereon, which form a part of this specification.

15 This invention relates to new and useful improvements in single reciprocating dashers for churning, and comprises various details of construction and combinations and arrangements of parts, which will be hereinafter fully described, and then specifically defined in the appended claims.

20 I illustrate my invention in the accompanying drawings, which, with the letters of reference marked thereon, form a part of this application, and in which—

25 Figure 1 is a vertical sectional view. Fig. 2 is a detail view of one end of the dasher shaft, and Fig. 3 is a sectional view on line 4 of Fig. 1.

30 Reference now being had to the details of the drawings by letter, A designates the body of a churn, and B the top, having an aperture C therein, in which is mounted a cylindrical shell C'.

35 E designates a hollow tubular shell having oppositely-disposed elongated slots E' therein, and through which slots a shaft F, which is journaled in suitable bearings in the top of the churn, is adapted to pass. Said shell E

40 is adapted to have a vertical play through the shell C'. A pin G passes centrally through the shell E, and a spring H is fastened at one end to said pin, and its other end is fastened to said shaft F, the office of said spring being normally to hold the shell E at its highest throw. K designates the shaft of the dasher, and the upper end thereof has flattened portions K' parallel to each other and adapted to engage corresponding flattened walls with-

45 50 in the lower end of said shell, in which it telescopes. A metallic band N is fitted over the end of said shaft, which telescopes within the shell and is fastened to said flattened surfaces. A pin O is adapted to pass through

registering apertures in the lower portion of 55 the shell and said flattened portions of the shaft, whereby the latter may be held to the shell, and forming means for readily detaching the same when it is desired to cleanse the dasher or for any other purpose.

60 L designates an angle-stepped bar fastened at its lower end to the shell, and its vertical portion is adapted to have a play in a suitable guide-slot formed in the top of the churn, and a bolt Q, fixed to the top B, is 65 adapted to engage one or another of the steps of said bar. By this provision it will be noted that the throw of the dasher may be limited to adapt the same for a short or a long stroke.

70 To the upper end of the shell is fastened a handle E², consisting of a straight cylindrical piece telescoping within said shell, forming means whereby an operator may take hold to operate the dasher.

75 From the foregoing it will be noted that by the provision of the apparatus shown and described a simple and efficient means is afforded for easily operating a churn-dasher, it merely being necessary to apply weight to 80 the dasher to cause the same to be depressed, the spring normally returning the dasher to its starting position, and by the provision of the means shown the throw of the shaft may be easily regulated.

85 What I claim is—

1. In combination with a churn and top having an aperture therein, a hollow shell passing through said aperture and provided with oppositely-disposed elongated slots, a 90 shaft passing through said top and slots, a spring fastened at one end to said shell below said slots and its other end fastened to said shaft, and a dasher having a shaft, the end of which is detachably held within the 95 lower end of said shell, as set forth.

2. In combination with a churn and top having an aperture therein, a hollow shell passing through said aperture and provided with oppositely-disposed elongated slots, a 100 shaft passing through said top and slots, a spring fastened at one end to said shell below said slots and its other end fastened to said shaft, a dasher having a shaft, the end of which is detachably held within the lower 105 end of said shell, and means for regulating the throw of the dasher, as set forth.

3. In combination with a churn and top

having an aperture therein, a hollow shell
passing through said aperture and provided
with oppositely-disposed elongated slots, a
shaft passing through said top and slots, a
5 spring fastened at one end to said shell be-
low said slots and its other end fastened to
said shaft, a dasher, a shaft therefor, the up-
per end of which has parallel flattened por-
tions adapted to telescope within the lower
10 end of said shell and engage the flattened

faces within said shell, and a pin passing
through registering apertures in the lower
portion of said shell and the upper end of the
dasher-shaft, as set forth.

In testimony whereof I hereunto affix my 15
signature in the presence of two witnesses.

WERNER ED WYNNE.
